Bassett & Smith,

Removing Carbon from Gas Retorts.

No. 80,438.

Patented July 28. 1868.

United States Patent Office.

JOHN A. BASSETT AND OLIVER C. SMITH, OF SALEM, MASSACHUSETTS.

Letters Patent No. 80,438, dated July 28, 1868.

IMPROVED METHOD OF REMOVING CARBON FROM GAS-RETORTS.

The Schedule referred to in these Letters Patent and making part of the same.

TO ALL WHOM IT MAY CONCERN:

Be it known that we, JOHN A. BASSETT and OLIVER C. SMITH, of Salem, in the county of Essex, and State of Massachusetts, have invented a new and improved Method of Removing Carbon from Gas-Retorts; and we do hereby declare the following to be a full, clear, and exact description of the same.

The object of this invention is to provide a means of easily and cheaply removing the accumulation of induced carbon from the interior of gas-retorts, and consists, for this purpose, of the use of a small direct-acting fan and steam-blower, of a form peculiarly adapted to the object desired, attached directly to the retort-lid, which is made with an opening and other appliances to receive it, by means of which a powerful current of mingled air and steam is injected into the retort, decomposing and disintegrating the carbonaceous deposit, loosening it from the wall of the retort, and clearing it in a comparatively short space of time.

By the present method of removing this deposit, which in most cases is to simply leave the retort open and allow a current of air to pass in and burn up the carbon, a great deal of time is lost, as the process is slow and imperfect, and the same fuel is used to heat the retort, whether making gas or not. With the apparatus which forms the subject of this application, the deposit is quickly removed, at a small expense, the retort is not injured, its application is readily made, and after being applied requires no attention until the process is complete.

To enable others skilled in the art to make and use our invention, we will proceed to describe the apparatus and its method of operation.

The drawing represents a vertical section of the retort, furnace, and accompanying apparatus, in which A is the gas-retort, set in the furnace B. On the top of the furnace, and extending along the entire line of benches, is a steam-main, C, communicating with a steam-boiler, from which steam is taken by means of a branch at each bench, a valve, D, being placed at each branch for controlling the supply. From this branch a flexible steam-pipe, E, connects with the steam-fan blower F. This blower is fastened to the lid of the retort G, from which a pipe, H, is carried nearly to the rear end of the retort, the blower F, lid G, and pipe H being securely fastened together so as to be placed on and removed from a retort in one piece.

The flexible pipe E allows the connection to be readily made, and the same blower to be used upon different retorts on the line of benches communicating with the steam-main C.

By having a number of these blowers, the operation of clearing may be going on simultaneously in any number of retorts at the same time.

This apparatus is used by placing the retort-lid, blower, and pipe on the mouth of the retort, and securing it, connecting the flexible steam-pipe with the blower and the branch of the steam-main, removing the plug I in the top of the stand-pipe J. Then, by letting on the steam, the blower is set in operation, forcing a current of air and steam through the pipe H into the retort, consuming and disintegrating the deposited carbon, the products escaping through the open stand-pipe.

The steam fan-blower has a hollow shaft, with hollow arms, bent in the form of the segment of a circle, the ends being open, the steam escapes, and by its reactive effect revolves the arms, upon which are placed the fans, injecting a current of air both by the fans and the injective effect of the steam-jets.

Having thus described our invention, we desire to claim, and secure by Letters Patent, as follows:

1. The apparatus shown and set forth, having the various parts constructed and operating substantially as specified, and used for the purpose described.
2. Combining an air-forcing apparatus with a retort-lid having an opening for the purpose of admitting air to the interior of the retort.
3. The combination of the pipe H and retort-lid G with the air-forcing apparatus F, when used for the purpose specified.
4. The combination of the flexible steam-tube E with the main, C, and blower F, for the purpose set forth.

JOHN A. BASSETT,
O. C. SMITH.
